UNITED STATES PATENT OFFICE.

JOHN M. BEACH, OF GRAND RAPIDS, MICHIGAN.

DESIGN FOR A RADIOCABINET.

Application filed November 13, 1926. Serial No. 19,715. Term of patent 3½ years.

To all whom it may concern:

Be it known that I, JOHN M. BEACH, a citizen of the United States, residing at No. 951 Ogden Street, S. E., Grand Rapids, in the county of Kent and State of Michigan, have invented a new, original, and ornamental Design for a Radiocabinet, of which the following is a specification, reference being had to the accompanying drawing, forming a part thereof, in which:—

A front view of the cabinet is shown in perspective, with one door open and the other door closed.

I claim:

The ornamental design for a radiocabinet substantially as shown.

JOHN M. BEACH.
